(57) **CLAIM**

The ornamental design for a condiment container, as shown and described.

DESCRIPTION

FIG. 1 is a perspective view of the condiment container showing our new design;

FIG. 2 is a bottom perspective view thereof;

FIG. 3 is a top view thereof;

FIG. 4 is a bottom view thereof;

FIG. 5 is a side view thereof;

FIG. 6 is a front view thereof; and,

FIG. 7 is a rear view thereof.

The broken line showing of structure is for illustrative purposes only, and forms no part of the claimed design.
